CLAIM

The ornamental design for a handbag, as shown and described.

DESCRIPTION

FIG. 1 is a top perspective view of the claimed base handbag with an exemplary interchangeable handbag cover shown in phantom in a closed, attached conformation about the base handbag;

FIG. 2 is a top perspective view thereof, with the exemplary interchangeable handbag cover shown in phantom in a partially opened, detached conformation about the base handbag;

FIG. 3 is an elevated front view of the base handbag shown in FIG. 1, with the opposing back view being a mirror image thereof;

FIG. 4 is a top, plan view thereof;

FIG. 5 is an elevated, left side view thereof, with the opposing right side being a mirror image thereof; and,

FIG. 6 is bottom view thereof.

The broken lines showing the interchangeable handbag cover is for illustrative purposes and forms no part of the claimed design.
